ROY W. SCHWEIKER, OF LANSDALE, PENNSYLVANIA.

DESIGN FOR A SIDE-WALL LIGHTING FIXTURE.

Application filed November 27, 1926. Serial No. 19,862. Term of patent 14 years.

To all whom it may concern:

Be it known that I, Roy W. SCHWEIKER, a citizen of the United States, residing at Lansdale, in the county of Montgomery and State of Pennsylvania, have invented a new, original, and ornamental Design for a Side-Wall Lighting Fixture, of which the following is a specification, reference being had to the accompanying drawings, forming a part thereof, in which:

Figure 1, is an end view;

Fig. 2, is a plan view;

Fig. 3, is a side view; and

Fig. 4, is a bottom view.

The dominant feature of my design is the effect produced by the relationship of the elongated rectangular base, the tapering neck having the alternating panels and ridges, and the peripherally smooth circular shade holder at the outer part of the neck where the panels and ridges terminate.

I claim:

The ornamental design for a side wall lighting fixture, as shown and described.

In testimony whereof I affix my signature.

ROY W. SCHWEIKER.
